Atty.

UNITED STATES PATENT OFFICE

JAMES C. DAWSON, OF WEBSTER GROVES, MISSOURI, ASSIGNOR TO ELMA N. DAWSON, OF WEBSTER GROVES, MISSOURI

LOOSE LEAF BINDER

Application filed April 29, 1931. Serial No. 533,716.

This invention relates to loose leaf binders and has for its object to provide a simple, effective means for attaching booster levers to loose leaf binders. It is particularly 5 adapted to loose leaf binders of the wire arch frame type.

Other objects and advantages will appear from the specification and the appended drawing in which—

10 Fig. 1 illustrates in perspective the loose leaf binder;

Fig. 2 is a bottom plan view of a wire arch frame loose leaf binder fitted with booster levers of a type which are herein proposed;

15 Fig. 3 is a vertical section through one end of the loose leaf binder on the line 3—3 of Fig. 2;

Fig. 4 is a vertical transverse section through the loose leaf binder on the line 20 4—4 of Fig. 3;

Fig. 5 is a bottom plan view illustrating the alternative form of booster lever as applied to binders of the wire arch frame type;

Fig. 6 is a vertical longitudinal section 25 through one end of a binder showing a further modified form of booster lever;

Fig. 7 is a transverse vertical section on the line 7—7 of Fig. 6;

Fig. 8 is a vertical longitudinal section 30 through the end of a loose leaf binder illustrating a still further modification of the booster lever; and

Fig. 9 is a transverse vertical section on the line 9—9 of Fig. 8.

35 The binder, generally indicated by 10, comprises a fabric or cardboard cover 11, to which is attached by any means the metal binding element 12. The cover 13 is a channel section having a crowned or arched web 14, and two vertical marginal flanges 15 and 16. Articulated wire arch frames 17 and 18 are retained within the cover and their ends, which project therethrough, terminate in the mating pairs of paper-holding prongs 19 and 21. A third pair of paper-holding prongs 22 and 23 may be affixed to the frames 17 and 18, if desired.

40 As best indicated in Fig. 2, a pin or rivet 24 is set through the flanges 15 and 16 adjacent the ends of the binder to support and

form a fulcrum for the booster lever 25 which bears the lugs 26, 26 adapted to receive the pin. The inner end 27 of the booster lever is arranged to press against the arch frames 17 and 18 and to lift them, while the outer end 55 28 terminates in the thumb piece 29 which extends beyond the cover.

The booster lever is prevented from moving sidewise on the pin by the end wall 31 of the cover, which is cut away at 32 only 60 enough to give the necessary clearance.

An alternative form of lever may be as shown in Fig. 5. In this form the booster lever is provided with integral trunnions 33, 33 which in effect form a pin pivoted in 65 the holes 34, 34 punched through flanges 150, 160.

In Fig. 6, the booster lever 35 may be formed with the transverse rib 36 which fits over the rivet or pin 240. After the rivet 70 is put in place, it is impossible to displace the booster lever, since its upper surface 37 engages the web 140 as shown in Fig. 7.

Lugs may be provided on the booster lever as shown in Fig. 8. These comprise two integral projections 38 which fit over and engage the transverse pin 41. To prevent the booster lever from being displaced after the pin has been put in position, its central portion may be bumped up as shown at 39. This 75 80 engages the web and prevents the lever from coming loose.

Another common form of wire arch frame loose leaf binder has inturned instead of vertical margins or flanges. It can well be appreciated that the angular position of the flanges with respect to the web is of negligible importance and that the form of booster lever and booster lever support herein illustrated is equally applicable to binders of the 85 90 95 inturned flange type.

What I claim, therefore, is:

1. In a loose leaf binder, a cover plate having marginal flanges, a pair of articulated toggle elements retained therein bearing mating pairs of paper-holding prongs extending through the plate, a pin forming a fulcrum extending between the flanges and a booster lever pivotally mounted by the pin and adapted to lift the toggle elements. 100

2. In a loose leaf binder, a cover plate having a web and marginal flanges, articulated toggle elements bearing mating pairs of paper-holding prongs maintained within the cover, and a booster lever having integral trunnions engaging the flanges extending beneath the web and adapted to lift the toggle elements.
3. In a loose leaf binder, a cover plate having a web and marginal flanges, articulated toggle elements maintained therein bearing mating pairs of paper-holding prongs, a pin extending between the flanges forming a fulcrum for a booster lever and a booster lever bearing lugs to engage the pin adapted to engage the toggle elements and to lift them and retained against displacement by the engagement of its upper surface with the web.
4. In a loose leaf binder, an arched cover plate with the crown up having downwardly turned marginal portions, a pair of articulated elements bearing mating pairs of paper-holding prongs, a booster lever extending beneath and pivoted upon the marginal portions of the cover plate and adapted to engage the articulated elements and to lift them.
5. In a loose leaf binder, a cover plate having down-turned marginal portions, a pair of articulated toggle elements therein, and a pivoted booster lever supported upon the down-turned marginal portions of the cover plate and adapted to engage the toggle elements and to lift them.

In testimony whereof I affix my signature.

JAMES C. DAWSON.
